UNITED STATES PATENT OFFICE.

ARVID R. NELSON, OF MEDIAPOLIS, IOWA.

JIFFY-BAND TOOL.

Application filed February 1, 1927. Serial No. 165,074.

This invention relates to a jiffy band tool.

The object of the invention is the construction of a tool adapted to be used in taking out bands of the demountable ear type, relining same, and then replacing the same, back in the automobile.

It is well known that it is a common practice among mechanics and others to use a screw driver or such tool, which has to be held or gripped with one hand allowing only one hand to be free to work with; this is only a make-shift method, as the screw driver is liable to slip out of place, or slip off, allowing the band and spring to kick off the washer and nut into the transmission case, which is very undesirable. Therefore, it is to produce a tool which will overcome the necessity of using such an inadequate tool as a screw driver, that I have perfected the present invention.

It is to be understood that with my new device (tool), the relining of Ford bands is greatly simplified, with respect to the operation of so doing. My improved tool is of a simple and relatively inexpensive structure to manufacture, is easy to use, positive in action, efficient and durable in service, and is a general improvement in the art.

With the foregoing and other objects in view, my invention comprises certain novel constructions, combinations and arrangements of parts as will be hereinafter fully described, illustrated in the accompanying drawings and more particularly pointed out in the appended claims.

In the drawings:

Figure 1 is a fragmentary view, showing my tool in operation, and with the pivoted jaw thereof in one position, while

Figure 2 is a perspective view of the tool, as it appears in operation, and shown with the pivoted jaw in a different position than shown in Figure 1.

Figure 3 is a perspective view of the tool, showing the same in its inoperative or closed position.

Figure 4 is a fragmentary view in elevation of the handle of the tool.

Figure 5 is a perspective view of the tool shown in a wide-open position with the piv-

oted jaw in a different position from that shown in Figure 3.

Figure 6 is a sectional view taken on line 6-6, Figure 5, and looking in the direction of the arrows.

Figure 7 is a view in elevation of a nut supporting tool.

Referring to the drawings by numerals, 1 designates the handle of the tool, which is 60 comparatively long and is twisted at 2 to form a forked inner end 3, at right angles to the main part of the handle 1; this forked end 3 is provided with a bifurcation 4, so that the forked end 3 can rest upon bolt 5, 65 as shown in Figures 1 and 2. The bolt 5 has its shank in the bifurcation 4 of end 3. In the handle 1 is an elongated aperture 6, which aperture is formed near the forked end 3. In the outer end of elongated aperture 6 is a notch 7. Handle 1 is also provided with a round aperture 8.

A pivoted jaw 9 is associated with handle 1. This jaw 9 has a rivet 10, which is slidably mounted in the elongated aperture 6, 75 The shank of the rivet 10 being adapted to ride in the notch 7 for the purpose herein-after specified. Jaw 9 has a flattened outer end 11. In opposite edges of the flat end 11 are notches 12 and 13. Each of these 80 notches has an inwardly extending hook 14. The rod-like main portion of jaw 9 and one edge only of the flat end 11 is provided with a row of teeth 15, for the purpose herein-after specified. It is to be noted that the 85 peculiar construction of teeth 15 on the flat portion 11, at one edge only thereof, is to allow the outer end of pawl 16 to engage these teeth irrespective as to the position of the jaw 9. This pawl 16 is pivotally 90 mounted on the rivet 17, which rivet is in aperture 8, Figure 4.

In Figure 7, I have shown a nut carrying tool, which comprises a handle 18 that is bent at 19 to provide an outstanding base 95 20. An externally threaded stud 21 has a portion extending through base 20, and with a head 22 formed on the outer end, holding the stud on the handle. This stud is provided with an outer "countersunk" or con-caved end 23, whereby the stud 21 can be held against the end of pedal shaft and the

operator can turn nut off of pedal shaft on to the threaded stud or stub shaft 21, which makes an easy job of a very hard one heretofore, as the nut can not be lost or dropped down out of sight when being taken off the pedal shaft, since it is securely located on the stud 21. In this way, the operator can remove adjusting nuts without dropping them. After the nut or nuts are on stud 21, to replace them hold the stud 21 against end of pedal shaft, and then turn the nuts, by means of a finger, onto the shaft. With this tool, an operator can work to great advantage, because time will be saved, and the operation of taking off or placing on the nuts will be greatly simplified.

In Figures 1 and 2, I have shown a transmission cover with plate removed. The tool is placed straight up or perpendicular with the pivoted jaw 9 engaging the screw or bolt 24; this bolt 24 in Figure 1, is shown in the notch 12, with its hook 14 preventing accidental displacement. In Figure 2, the bolt 25 is positioned in the notch 13. When the tool is in the position shown in Figure 1, the shank or rivet 10 will be resting in the notch 7, whereas when the tool is in the position shown in Figure 2, the rivet will be in the lower or inner end of elongated aperture 6. By reason of the peculiar forming of the teeth 15 on the "edge" of the flat end 11 and body of jaw 9, the tool can be placed in an upright or vertical position. As the transmission cover is higher at front or sloping towards the back, when the tool is placed over either screw or bolt 24 or 25, as shown in Figures 1 and 2, the peculiar construction of jaw 9, with its arrangement of teeth 15, allows the handle 1 to stand straight upright, so as to be out of the way as much as possible; also as the bands are up and down, this keeps the tool perpendicular with the bands.

My tool is adapted to assume the two positions shown in Figures 3 and 5, only in Figure 3 the pawl 16 should be engaging at its outer end the innermost teeth 15. These two positions of the tool are desirable, because the transmission cover is higher above the reverse band than at brake band, while raising rivet 10 in slot or aperture 6, so that it will seat in notch 7 for reverse band, and dropping rivet 10 to the lower end of slot 6, as shown in Figure 5, makes it adaptable for brake band; this adjustment makes the tool capable of removing both bands; the pawl 16 locking the tool in both positions.

It is to be noted that where the flattened portion 11 merges with the rod-like body of jaw 9, it has the appearance of being twisted, which, when the jaw 9 is swung to its wide open position causes the outer end of pawl 16 to engage one edge only of the flattened end 11 and that edge is the one provided with teeth 15.

While I have described the preferred embodiments of my invention and illustrated the same in the accompanying drawings, certain minor changes or alterations may appear to one skilled in the art to which this invention relates during the extensive manufacture of the same, and I, therefore, reserve the right to make such alterations or changes as shall fairly fall within the scope of the appended claims.

What I claim is:

1. In a tool of the class described, the combination of a handle, a jaw provided with bolt receiving notches pivotally mounted upon said handle, and a pawl pivotally mounted on said handle and adapted to engage said jaw.

2. In a tool of the class described, the combination of a handle provided with an elongated aperture, and having a notch at one end of said aperture, a jaw provided with teeth and a rivet, said rivet slidably mounted in said elongated aperture and adapted to be seated in said notch, and a pawl carried by said handle and adapted to engage the teeth of said jaw.

3. In a tool of the class described, the combination of a handle provided with a twisted portion terminating in a forked end, said forked end positioned at right angles to the handle, said handle provided near said forked end with an elongated aperture, said aperture terminating at its outer end in a notch, a jaw movable along side of said handle and provided with a rivet extending through said elongated aperture, and adapted to be seated in said notch, and a pawl carried by said handle and adapted to engage and limit pivotal movement of said jaw.

4. In a tool of the class described, the combination of a handle, a jaw pivotally mounted on said handle, said jaw having a rod-like body and terminating at its outer end in a flattened portion, said flattened portion provided in opposite edges with notches, said flattened portion having a hook extending inwardly at each notch, said rod-like body and flattened portion provided with teeth, said teeth on the flattened portion being located only at one edge, and a pawl pivotally mounted on said handle and adapted to engage all of said teeth.

5. In a tool of the class described, the combination of a handle, a jaw pivotally mounted upon said handle, said jaw being slightly twisted intermediate its length and formed with a flattened portion at its outer end, teeth on the upper face of said flattened portion at one edge only and also formed upon the top of the body of said jaw, said flattened portion having a bolt receiving notch to one side of said teeth and a second bolt receiving notch on the same side but beyond the teeth and near the outer end of the flattened portion, and a pawl pivotally

mounted on said handle and adapted to engage all of the teeth.

6. In a tool of the class described, the combination of an elongated handle provided with an inner forked end, a notched jaw, a pawl engaging one and the same side of said handle, rivets extending laterally from

said jaw and pawl and through said handle, and the pawl adapted to engage the jaw for holding the jaw against pivotal movement **10** when the tool is in operation.

In testimony whereof I hereunto affix my signature.

ARVID R. NELSON.
